United States Patent Office

Des. 220,846
Patented June 1, 1971

220,846

BOWL

Joseph Anthony Mascetti, Jr., Geneva, Ill., assignor to American Can Company, New York, N.Y.

Filed Oct. 23, 1966, Ser. No. 19,682

Term of patent 14 years

Int. Cl. D7—01

U.S. Cl. D44—15

FIG. 1

FIG. 2

FIG. 3

FIG. 4

FIG. 5

FIG. 1 is a perspective view of a bowl showing my new design;

FIG. 2 is a top plan view thereof;

FIG. 3 is a side elevation view thereof;

FIG. 4 is a bottom plan view thereof;

FIG. 5 is an enlarged sectional view taken substantially along line 5-5 of FIG. 2.

I claim:

The ornamental design for a bowl, substantially as shown.
